BURNER VALVE DEVICE

James Maynard, Hawthorne, Calif., assignor to
Elgin Rowland Parker, Seal Beach, Calif.

Application April 7, 1941, Serial No. 387,241

13 Claims. (Cl. 236—48)

1

My invention relates to the valve art and more particularly to a valve mechanism of the thermostatic type. The invention finds particular utility in the gas water heater art, and, for the purpose of illustration, its use in such art is described hereinafter, it being understood that the invention is susceptible to other and different uses and is not limited to the specific embodiments or use shown and described herein.

Gas water heaters of the storage type normally are provided with a hot water reservoir in which a supply of water is maintained at a predetermined desired temperature by a main gas burner positioned in proximity to the water reservoir, the flow of gas to the main burner being controlled by a suitable thermostatic control mechanism operating a main burner valve and there being a suitable pilot burner adapted to ignite the gas to the main burner when gas is admitted to the main burner by the main burner valve.

A primary object of my invention is to provide an improved thermostatically operated valve mechanism particularly adapted to be used in connection with such a gas water heater for controlling the passage of gas to the main burner.

A further object of my invention is to provide such a valve mechanism in which the predetermined temperature of the water in the reservoir at which the thermostatically operated valve is actuated to pass gas to the main burner may be quickly and readily varied without disassembling the valve mechanism.

A further object of my invention is to provide a valve device including a housing having a chamber therein in which is disposed a valve seat and a snap valve element adapted to snap between open and closed positions on the seat to control the passage of gas therethrough. It is also an object of the invention to provide such a device in which the valve seat is axially movable within the housing chamber without disassembling the valve mechanism to vary the temperature of the water at which the valve element is automatically moved to open position.

Another object of my invention is to provide a valve mechanism of the class described which includes a housing with a chamber therein in which there is positioned a valve seat and a snap valve element adapted to be actuated between closed and open positions relative to said seat by thermostatic control means connected to the snap valve element to operate the same in response to changes in temperature of the control means. A further object is to provide such a

2

device in which a movement multiplying mechanism is interposed between the thermostatic control means and the snap valve element so that very slight movement of the thermostatic control means in response to temperature variations will produce a substantial amount of movement in the motion multiplying mechanism to operate the snap valve element. It is a purpose also to provide in such a construction safety or relief means

5 for the movement multiplying mechanism limiting to a predetermined value the movement and force communicated by the multiplying mechanism from the thermostatic control means to the snap valve element.

10 Gas water heaters of the storage type are normally provided with a main valve adapted to admit gas to the main burner of the heater, sometimes referred to in the art as an "A" valve, a pilot valve adapted to admit gas to the pilot 15 burner of the heater, sometimes described in the art as a "B" valve, and a thermostatically controlled valve for controlling the flow of gas to the main burner independently of the "A" valve, and in response to and as a function of temperature 20 changes in the water in the heater, there being separate and independent controls for each of such valves.

25 It is an object of my invention to provide a valve mechanism of the class described in which 30 the main valve and the pilot valve may be controlled, and the operation of the thermostatic control valve varied by a single manual control element. More specifically, one of the purposes 35 of the invention is to provide such a valve mechanism in which a single manual control element is employed to actuate the pilot valve from closed to open position while the main valve is closed, to actuate the main valve to open position when and only when the pilot valve is open, to adjust 40 the thermostatically controlled valve to vary the temperature at which it is automatically actuated to open position, and to vary the degree of opening of the main valve as a function of such temperature.

45 A further object of my invention is to provide a valve mechanism in which any leakage of gas through the pilot valve or main valve cannot escape into the atmosphere surrounding the valve mechanism but is confined to the flow lines leading to the burners of the heater. Another object of my invention is to provide a valve mechanism for use in hot water heaters having a connection between the valve housing and the gas discharge line therefrom, permitting the ready 50 variation of the degree of communication between

the housing and such line without disassembling the line from the housing or impairing the sealed relationship therebetween. Other objects include the provision of a valve mechanism of the type described, which is inexpensive to manufacture, easy to assemble, and simple to adjust.

Other objects and advantages of my invention will be made apparent by the following description, which may be better understood by reference to the accompanying drawings in which:

Fig. 1 is an elevational view of one embodiment of my invention;

Fig. 2 is a sectional view taken as indicated by the line 2—2 of Fig. 1;

Fig. 2 is a sectional view similar to Fig. 2, showing the snap valve in open position;

Fig. 4 is a fragmentary sectional view taken as indicated by the line 4—4 of Fig. 2, showing the valve mechanism in closed position;

Fig. 5 is a fragmentary sectional view similar to Fig. 4, showing the valve mechanism in position passing gas to the pilot burner and preventing the passage of gas to the main burner;

Fig. 6 is a fragmentary sectional view similar to Figs. 4 and 5, showing the valve mechanism in position passing gas to the pilot burner and also passing gas to the main burner to maintain the water in the reservoir at the temperature corresponding to the "cold" position of the valve;

Fig. 7 is an end elevational view of the motion multiplying means of my invention;

Fig. 8 is a sectional view taken as indicated by the line 8—8 of Fig. 7; and

Fig. 9 is a sectional view of another embodiment of my invention.

Referring to the drawings, which are for illustrative purposes only, the numeral 11 indicates a valve housing including a shell 12 and a back plate 13. The back plate 13 is seated upon an annular gasket 14 against a shoulder 15 in the shell 12 and secured in place by a lock nut 16 threaded to the shell 12 and bearing against the outer surface of the back plate 13. Instead of lock nut 16, bolts 12a illustrated in Fig. 1 may be employed to secure the back plate 13 to the shell 12, a plurality of openings (not shown) for the reception of the bolts being provided in the back plate 13 so that the shell 12 may be shifted relative thereto into proper position when the back plate 13 is connected to the water reservoir. Such an angular adjustment of the shell 12 and back plate 13 may also be made if the lock nut 16 is employed. The shell 12 is provided with an inlet opening 17 provided with interior threads 18 for the reception of the threaded end of a gas inlet pipe 19. The shell 12 is provided also with an outlet opening 20 for discharging gas to a main burner, and an outlet opening 21, indicated by dotted lines in Figs. 4 to 6, inclusive, for discharging gas to a pilot burner.

Within the shell 12 and formed integrally therewith is a wall means or wall member 22, having therein a port 23 communicating through a first chamber or passage 24 in the shell 12 with the inlet opening 17. As is best illustrated in Figs. 2 and 3, the front wall 25 of the shell 12 is flared outwardly or forwardly around the passage 24 and inlet opening 17, and the inner surface of the wall member 22 is in the plane of the inner surface of the front wall 25 radially opposite. A second chamber 24a is defined in the shell 12 between the back plate 13 and the wall member 22. Engaging the inner surface of the wall member 22 and that inner surface of the front wall 25 in the same plane is a valve plate

or valve member 26. The valve member 26 has formed therein an opening 27 adapted for movement into and out of registry with the port 23 during rotation of the valve member 26. Formed centrally upon the valve member 26 and projecting forwardly therefrom is a cylindrical sleeve 28 projecting through a cylindrical opening 25a in the front wall 25 of the shell 12 and having formed therein a cylindrical bore 29 with an enlarged portion 30 at its inner end. Rotatably mounted within the cylindrical bore 29 is a projecting portion 31 of an adjusting plug 32, having an enlarged head 33 with a portion thereof seated in the enlarged portion 30 of the cylindrical bore 29, and the remainder thereof projecting inwardly therefrom and having thereon a coarse thread 34.

Threadedly secured to the enlarged head 33 of the adjusting plug 32 is a valve support 35. The valve support 35 has therein a groove 36 in which there is secured in fluid-tight relationship therewith the inner edge of an annular diaphragm 37. The outer edge of the diaphragm 37 is retained in fluid-tight relationship with an inwardly extending annular flange 38 in the shell 12 by a resilient clamping ring 39 engaging the inner wall of the shell 12 and the inner surface of the back plate 13. As illustrated in the drawings, the clamping ring 39 is U-shaped in cross-section, the apex of the U being directed inwardly, and is provided with a plurality of openings 40 for the passage of gas therethrough.

The diaphragm 37 is likewise provided with a plurality of openings 41 spaced around the enlarged head 33 of the adjusting plug 32 and adjacent thereto. The diaphragm 37 is formed of any suitable resilient material, and I have found that the synthetic rubber product known as neoprene is well adapted for this use. The clamping ring 39 may be made of any suitable resilient material, such as neoprene, or thin metal.

The diaphragm 37 is provided with an annular valve seat 42 which may, as illustrated in the drawings, be formed as a rearwardly extending annular convex portion, preferably of a thickness permitting its deformation into sealing contact with a movable valve member or valve disc, as illustrated in Fig. 2.

Engaging the inner end of the valve support 35 of the adjusting plug 32 is a snap valve or movable valve element in the form of a disc 43. The disc is made of metal in concavo-convex form and is adapted, upon the application of pressure near the center thereof, to snap from the position illustrated in Fig. 2 in which it is concaved forwardly to the position illustrated in Fig. 3 in which it is concaved rearwardly. The valve disc 43 is of a diameter such that, when it is concaved forwardly, its peripheral edge engages the valve seat 42 in sealing engagement therewith, preventing the passage of gas through the openings 41 in the diaphragm 37. The inner end of the valve support 35 of the adjusting plug 32 is provided with a cavity 44 shaped to conform to the valve disc 43 when it is concaved rearwardly and resists further deformation of the valve disc 43 rendering it more concave rearwardly. Means for resiliently urging the valve disc 43 into contact with the valve support 35 are provided in the form of a spring 45 helically wound and with its outer end bearing against a carrier plate 46 of a motion multiplying mechanism or means 47.

As is best illustrated in Figs. 7 and 8, the carrier plate 46 has formed therein a central opening 48 and has a pair of inwardly extending ver-

tical lugs 49 on the inner surface thereof, one on each side of the opening 48. Pins 50 and 51 connect the upper and lower ends of the lugs 49 and support thereon a plurality of interengaging levers adapted to transmit motion and, during such transmission, to multiply and enlarge such motion, so assembled as to permit the use of short rigid levers.

As illustrated in the drawings, a first lever 52, U-shaped in cross-section, is pivoted to the upper pin 50 and extends across the opening 48 in the carrier plate 46. Its lower end engages a second lever 53 pivoted upon the lower pin 51. The contact between the first lever 52 and the second lever 53 is adjacent the pivoted end of the lever 53, so that movement of the lever 52 causes a greater movement of the free end of the lever 53. The free end of the lever 53 engages a third lever 54 adjacent its point of pivoting upon the upper pin 50. The third lever 54 in turn engages a fourth lever 55, U-shaped in cross-section, adjacent its point of pivoting upon the lower pin 51. The free end of the fourth lever 55 contacts the snap disc 43 centrally thereof for actuating it between its closed position, illustrated in Fig. 2, and its open position, illustrated in Fig. 3, and is so formed that the locus on the disc 43 contacted by the fourth lever 55 remains the same at all positions of the lever. It will be understood that while I have illustrated the interengaging levers as four in number, a greater or lesser number may be employed to provide the desired effect.

Motion is imparted to the motion multiplying means 47 by a control element having a portion thereof movable in response to temperature variations of the water to be heated. This control element may be of any of a variety of constructions, moving towards the motion multiplying means 47 as the temperature of the water being heated decreases and away from such means as such temperature increases or vice versa. The control element as illustrated in the drawings is indicated generally by the number 56 and is immersed in the water in the storage tank by connection to a plug 57 projecting rearwardly from the back plate 13 and threaded into a boss 58 in the wall 59 of the water reservoir. The plug 57 is provided with a central passage including a cylindrical portion 60, an intermediate threaded portion 61, and an enlarged cylindrical portion 62. Threadedly secured in the intermediate portion 61 is a tube 63, the end of which is sealed by a screw cap 64. Solder may be placed within the enlarged cylindrical portion 62 around the tube 63, as indicated by the numeral 65, to insure the sealing of the tube to the plug 57 if desired.

Disposed within the tube 63 is a rod 66 having one end bearing against the inner side of the screw cap 64 and the other end adapted for projecting through the opening 48 in the carrier plate 46 into contact with the first lever 52. The tube 63 is preferably made of material having a high coefficient of linear expansion, such as copper, and the rod 66 is preferably made of material having a low co-efficient of linear expansion, such as Invar or other suitable nickel steel.

As the temperature of the water in the reservoir diminishes, it will be apparent that the tube 63 will diminish in length more than the rod 66, and thus move the inner end of the rod 66 in a 70 direction urging the first lever 52 of the motion multiplying means 47 inwardly of the housing 11.

Non-rotatably secured by a key 67a to the sleeve 28 of the valve member 26 forwardly of the housing 11 is an operating lever 67. The

projecting portion 31 of the adjusting plug 32 extends beyond the outer end of the sleeve 28 providing a squared portion 68, and a threaded portion 69 adjacent the end thereof. A slot 69a is formed in the end of the projecting portion 31 to receive a screw driver to effect its rotation relative to the valve member 26. Positioned upon the squared portion 68 is a spring washer 70 having a square opening therein which is urged into resilient engagement with the operating lever 67 by a lock nut 71. A lock screw 72 is threaded into the operating lever 67 against the spring washer 70, thus securing the operating lever against rotation relative to the adjustment plug 32.

The valve member 26 is resiliently urged into sealing engagement with the wall member 22 by a helical compression spring 73, one end of which engages the rearward surface of the valve member 26 and the other end of which engages the forward surface of the annular flange 38 in the shell 12. The forward surface of the valve member 26 is provided with an arcuate groove 14 best illustrated in Figs. 4 to 6 inclusive. The groove 14 is so positioned in the valve member 26 relative to the opening 21 therein as to connect the port 23 in the wall member 22 with the opening 21 in the shell 12 at all positions of the valve member 26 at which the opening 21 therein registers with the port 23 in the wall member 22 and during some of the rotation of the valve member 26 before the opening 21 therein commences to register with the port 23.

The outlet opening 20 in the shell 12 is connected to a discharge pipe 75 delivering gas from the housing 11 to the main burner of the heater by the connection indicated generally by the numeral 76. The connection 76 includes a deformable body 77 having an opening 78 therethrough, the lower end 79 of which is located centrally of the body 77 and the upper end 80 of which is displaced relative to the axis of the body 77. The body 77 is formed of a resilient material, such as neoprene or the like, and is provided at its outer periphery with an upper beveled portion 81 and a lower beveled portion 82. The body 77 is confined within a compressing member 83 which extends between the upper and lower beveled portions 81 and 82 and compresses the body 77 to less than its normal external diameter. An outwardly declining annular valve seat 84 is formed on the shell 12 around and eccentric with the main burner outlet 20 therein, and the upper beveled portion 81 of the body 77 is adapted to engage the annular seat 84 when the upper end of the body contacts the shell 12 around the outlet opening 20. The end of the discharge pipe 75 communicating with the main burner is flared as indicated by the numeral 85, and this flared portion is adapted to engage the lower beveled portion 82 of the body 77 and the lower end of the compressing member 83. Surrounding the flared portion 85 is a collar 86 supported upon a yoke 87 adjustably secured to the shell 12 by a bolt 88. When the bolt 88 is threaded into the shell 12, the yoke 87 is moved upwardly, clamping the collar 86 and flared portion 85 of the discharge pipe 75 and the compressing means 83 firmly against the shell 12 and compressing the body 77 vertically into sealing engagement with the flared portion 85 and the shell 12. The outer surface of the compressing member 83 is knurled to facilitate the rotation of the compressing member and the body 77 relative to the shell 12 and the flared portion 85 of the discharge pipe 75.

to vary the degree of registration of the upper end 80 of the passage through the body with the outlet opening 20 in the shell 12 to vary the rate of passage of gas therethrough to the main burner.

The outlet opening 21 in the shell 12 is connected to a discharge pipe 89 conveying gas to the pilot burner by a connection indicated generally by the numeral 90 identical in construction with the connection 76 previously described and not illustrated in detail in the drawings.

In the construction previously described, the wall member 22 and the port 23 therein cooperate with the valve member 26 and the opening 27 therein as a main valve means or "A" valve controlling the passage of gas from the inlet pipe 19 to the main burner; the wall member 22 with the port 23 therein and the valve member 26 with the arcuate groove 74 therein cooperate as an auxiliary valve means or "B" valve controlling the passage of gas from the inlet pipe 19 to the pilot burner; and the diaphragm 37 with its openings 41 and its valve seat 42 thereon cooperates with the valve disc 43 as an automatic valve means, and with the control element 56 and the motion multiplying means 47 acts as an automatic thermostatic valve means.

An indicia plate 91 is secured to the front wall 25 of the shell 12 and is provided with five indentations 92 to 96 adapted for the reception of a detent 97 illustrated in Fig. 9 and carried by the operating lever 67. The indentations 92 to 96 correspond respectively to the position of the valve mechanism in which no gas is permitted to flow to either the pilot or main burners, to its position in which gas is permitted to flow only to the pilot burner, to its position in which gas is permitted to flow to the pilot burner and permitted to flow to the main burner to maintain the water in the reservoir at the lowest predetermined temperature, to its position in which gas is permitted to flow to the pilot burner and to the main burner to maintain the water in the reservoir at the intermediate predetermined temperature, and to its position in which gas is permitted to flow to the pilot burner and to the main burner to maintain the water in the reservoir at the maximum predetermined temperature.

With the lock screw 72 removed and the construction otherwise assembled, as illustrated in Figs. 2 and 3, the automatic valve means of my valve mechanism is adjusted by inserting a screwdriver in the slot 69a in the end of the adjusting plug 32 and rotating the plug, thus moving the valve support 35 toward or away from the motion multiplying means 47. The valve support 35 carries with it the inner portion of the diaphragm 37 and the valve disc 43. The valve disc is retained in contact with the valve seat 42 by the compression spring 45, even though the valve support 35 and lever 55 are moved out of contact with the valve disc 43. It will be apparent that if the valve support 35 is thus moved toward the motion multiplying means 47, the temperature of the water in the reservoir and the temperature of the control element 56 at which the valve disc 43 will be snapped to open position, permitting gas to flow to the main burner, will be increased. It will be seen also that if the valve support 35 is moved away from the motion multiplying means 47, the temperature of the water in the reservoir and the temperature of the control element at which the valve disc 43 will be snapped to open position will be decreased. The valve support 35 is in this manner adjusted until it is so posi-

tioned that the valve disc 43 will be actuated to open position by the control element 56 and motion multiplying means 47 at that temperature of the control element 56 which is the lowest temperature at which it is desired to maintain the water in the reservoir. The operating lever 67 is then rotated until the detent 97 is received in the indentation 94 and the adjusting plug 32 is then locked against rotation relative to the operating lever 67 by tightening the lock screw 72 against the spring washer 70.

With the parts so adjusted when the operating lever 67 is moved so that its detent 97 engages the indentation 92, the valve member 26 is rotated to the position illustrated in Fig. 4 in which the annular groove 74 therein is out of registry with the outlet opening 21 and gas is thus prevented from flowing to the pilot burner, and the opening 27 therein is out of registry with the port 23 in the wall member 22, thus preventing the passage of gas to the main burner. If the operating lever be now rotated so that its detent 97 is received in the indentation 93, the valve member 26 is rotated to the position illustrated in Fig. 5 in which the arcuate groove 74 connects the port 23 of the wall member 22 with the outlet opening 21 in the shell 12, thus permitting gas to pass from the inlet pipe 19 to the discharge pipe 89, conveying gas to the pilot burner. In this position of the valve member 26 the opening 27 therein is out of registry with the port 23 of the wall member 22 so that gas is prevented from passing to the main burner.

When the operating lever 67 is rotated so that its detent 97 is received in the indentation 94, the valve member 26 is rotated to the position illustrated in Fig. 6, in which the arcuate groove 74 connects the port 23 of the wall member 22 with the outlet opening 21 in the shell 12, thus passing gas to the pilot burner. In such position of the valve member 26, the opening 27 therein registers with the port 23 of the wall member 22, and gas is permitted to pass through the opening 27. The rotation of the operating lever 67 to this position rotates the adjusting plug 32 so that the valve support 35 is advanced toward the control element 56 to that position in which the control element 56 through the motion multiplying means 47 actuates the snap valve disc 43 to open position at a relatively low temperature of the water in the reservoir. Only when the temperature of the water in the reservoir falls below this relatively low value is the valve disc 43 opened, permitting gas to pass to the main burner. When the temperature of the water in the reservoir increases above such relatively low temperature, the tube 63 expands and the pressure exerted by the rod 66 upon the motion multiplying means 47 is relieved, permitting the valve disc 43 to snap to its closed or normal position.

If now the operating lever 67 is rotated until its detent 97 is received in the indentation 95, the valve member 26 is rotated and the opening 27 remains in registry with the port 23 in the wall member 22, thus permitting gas to pass therethrough. This same movement of the operating lever 67 by rotation of the adjusting plug 32 moves the valve support 35 nearer the control element 56 and thus increases the temperature at which the valve disc 43 is automatically snapped to open position, as previously described. At this position of the mechanism the water in the reservoir is automatically maintained at a higher temperature than in that position of the mechanism described in the last paragraph. During this posi-

tion the arcuate groove 74 in the valve member 26 continues to connect the port 23 of the wall member 22 with the outlet opening 21 in the shell 12 and to thus supply gas to the pilot burner.

When the operating lever 67 is moved to its last position, in which its detent 87 is received in the indentation 88, the valve member 26 is rotated with the opening 27 remaining in registry with the port 23 in the wall member 22. Such rotation of the operating lever rotates the adjusting plug 32 moving the valve support 35 further toward the control element 58 and thus further increasing the temperature at which the valve disc 43 is snapped to open position, as hereinbefore described. In this position the water in the reservoir is automatically maintained at the highest predetermined temperature, and when the automatic valve means is in open position, gas is supplied to the main burner at the maximum rate. In this position also, the arcuate groove 74 continues to connect the port 23 with the outlet opening 21 in the shell 12 and to supply gas to the pilot burner.

The carrier plate 46, cooperating with the spring 45, acts as a relief means or limiting means for the motion multiplying means 47 by limiting the force and movement transmitted by the motion multiplying mechanism to the valve disc 43. If the tube 63 contracts to such an extent that the inner end of the rod 66 moves into the opening in the carrier plate 46 to a sufficient distance to exert an unduly large force upon the motion multiplying means 47 and the valve disc 43, the resistance of the spring 45 is overcome, and the carrier plate 46 is moved inwardly. This movement of the carrier plate 46 diminishes or eliminates the multiplication of movement transmitted by the motion multiplying means 47 and may operate to take up all of the movement of the rod 66 during a portion of its travel, so that none of the movement is transmitted to the levers 52 to 55, inclusive. The spring 45 is formed to provide a resistance to inward motion of the carrier plate 46 which may be overcome by a force less than that force which will have a damaging effect upon the levers 52 to 55 or the valve disc 43.

The cavity 44 on the valve support 35 is shaped to conform to the convex side of the valve disc 43 when the disc is concave rearwardly, as illustrated in Fig. 3, and to thus support the disc against excessive deformation during the continued application of force thereto by the motion multiplying mechanism.

It will be seen that, if there is any leakage of gas between the valve member 26 and the wall member 22 or through or around the diaphragm 37, such gas is prevented from escaping to the atmosphere around the valve mechanism by virtue of the fluid-tight housing 11 and is directed to the main burner or pilot burner which is customarily vented to the outside of the building. If desired, a packing 88 may be positioned in the enlarged portion 30 of the cylindrical bore 29 in the valve member 26 to insure that no gas can leak between the adjusting plug 32 and the valve member 26.

When the valve mechanism is installed and ready for use, the compression member 83 and the body 17 of the connection 16 may be rotated relative to the housing 11 and the discharge pipe 75 to the main burner to vary the degree of registration of the upper end 80 of the passage 78 with the outlet opening 20 in the shell 12 to adjust the rate of passage of gas therethrough in accordance with the gas pressure at the place of

use. In a similar manner the connection 90 between the housing 11 and the discharge pipe 89 leading gas to the pilot burner may be adjusted independently of the adjustment of the connection 78.

In the embodiment illustrated in Fig. 9 the numeral 101 indicates the housing of the valve mechanism which includes a shell 102 and a back plate 103. The shell is provided with an interior wall means or wall member 104 similar to the wall member 22 previously described. The wall member 104 has therein a port 105 communicating through a passage 106 with an inlet opening 107 in which an inlet pipe 108 is threaded. In sealing engagement with the inner surface of the wall member 104 and the inner surface of the front wall 109 of the shell radially opposite is a valve member 110 having an opening 111 therein adapted to move into and out of registry with the port 105 when the valve member 110 is rotated relative to the wall member 104. The valve member 110 includes a central cylindrical projection 112 extending through a central opening 113 in the front wall 109 of the shell, and an operating lever 114 is secured by a set screw 115 to the forward end of this projecting portion.

The opening 113 includes an enlarged portion 116 having therein a packing gland 117 in sealing relationship with the front wall 109 and the valve member 110. Also positioned in this enlarged portion 116 is a compression spring 118 urging the operating lever 114 outward and thus resiliently urging the valve member 110 into sealing engagement with the wall member 104 and the front wall 109 of the shell 102.

Formed centrally upon the inner side of the valve member 110 is a cylindrical projection 119 having therein a cavity 120 shaped to conform to a valve disc 121 when the valve disc is concaved inwardly. The periphery of the valve disc 121, when it is concaved outwardly, as illustrated in Fig. 9, is seated upon an annular valve seat 122 of resilient material, such as neoprene or the like. The valve seat may be formed substantially U-shaped in cross-section, the legs of the U extending into an annular channel 123 formed in the valve member 110. Clamped to the peripheral wall of the valve member 110 by a set screw 124 is a spider 125 having a central sleeve 126. The sleeve 126 is provided with a central projection 127 engaging the center of the valve disc 121, and with interior threads 128 in its inner end. An adjusting plug 129 has exterior left hand threads 129a engaging the threads 128 and its outer end bears against the center of the valve disc 121 and its inner end engaging a motion multiplying means 130. A compression spring 125a has one end bearing against the spider 125 and its other end engaging the valve disc 121 opposite the cylindrical projection 119, holding the valve disc 121 against such projection when the central projection 127 of the sleeve 126 is out of contact with the valve disc.

Connected in fluid-tight relationship with the adjusting plug 129 adjacent its inner end is a resilient diaphragm 131, the peripheral edge of which is clamped between the shell 102 and the back plate 103 by a lock nut 132 threaded into the shell 102. The diaphragm 131 is imperforate and is provided with circumferential corrugations, as indicated at 133, to more readily permit the axial movement of the adjusting plug 129. A compression spring 134 is provided with one end bearing against the diaphragm 131 adjacent the shell 102 and the other end bearing

against a carrier plate 135 of the motion multiplying means 130. The motion multiplying means 130 includes levers 136 to 138, inclusive, mounted and operating like the levers 51 to 55, inclusive, previously described. Extending through a central opening 140 in the carrier plate 135 is a rod 141 of a control element 142. A tube 143 is secured to the rod 141 as in the first embodiment. The tube 143 is threaded into a boss 144 and sealed therein with solder 145. The boss 144 is formed upon the back plate 103 and threaded into a wall 146 of the water storage reservoir.

The shell 102 is provided with an outlet opening 147 for discharging gas therefrom to the main burner through a connection 148 and a gas discharge pipe 149. This connection 148 is like the connection 77 previously described. The shell 102 is also provided with an outlet opening for discharging gas to the pilot burner and a connection at such opening between the shell and the gas discharge pipe, which opening and connection, being exactly like the opening 21 and connection 90 hereinbefore referred to, are not illustrated in the drawings.

In this embodiment of my invention the registration of the port 105 and the opening 111 in the valve member 110 is controlled by the operation lever 114, and the rotation of the operating lever 114 moves the adjusting plug 129 axially to vary the effective length of the connection between the motion multiplying means 130 and to thus vary the predetermined temperature at which the valve disc 121 is snapped to open position. The control element 141 and the motion multiplying means 130 in this embodiment of my invention function exactly like the control element and motion multiplying means described in relation to the first embodiment of my invention.

In both embodiments of my invention the areas of registration of the ports passing gas to the main burner are made substantial so that there is practically no decrease in pressure in the valve mechanism on the gas passing therethrough to the main burner.

A tapered valve body or member with radial ports communicating with axial passages therein may be employed instead of the cylindrical valve members 28 and 110 if desired.

While those embodiments of my invention hereinbefore illustrated and described are fully capable of performing the objects and providing the advantages primarily stated, it is to be understood that there are various other embodiments likewise capable of performing such objects and providing such advantages, and that my invention is therefore not restricted to the specific embodiments hereinbefore described.

I claim as my invention:

1. In a thermostatically controlled valve mechanism, the combination of: a housing having inlet and outlet openings therein; wall means in said housing between said openings, said wall means having a port therein; a valve member having an opening therethrough, said valve member engaging said wall means and being movable relative thereto for varying the registration of said opening therein with said port; a valve support in said housing; a valve seat in said housing; a valve disc engaging said support and adapted upon the application of a predetermined pressure for snapping from closed position in sealing engagement with said valve seat and closing communication between said openings in said housing to open position free of

said valve seat and permitting communication between said openings in said housing; a control member movable in response to temperature variations; motion multiplying means transmitting the movement of said control member to said valve disc so long as the resistance to movement of said disc is less than a predetermined value; and operating means exterior of said housing adapted for simultaneously moving said valve member and said valve support whereby the registration of said opening in said valve member with said port in said wall means is controlled and the temperature of said control member at which said valve disc is snapped to open position is varied.

2. In a thermostatically operated valve mechanism for controlling the passage of gas between an inlet pipe and a main burner and a pilot burner of a water heater, the combination of: a housing having an inlet opening, a main outlet opening, and an auxiliary outlet opening for connection to such inlet pipe, main burner, and pilot burner respectively; wall means in said housing between said inlet opening and said outlet openings, said wall means having a port therein; a valve member engaging said wall means and being movable relative thereto, said valve member having an opening therethrough adapted for registration with said port during movement of said valve member for controlling the passage of gas from said inlet pipe to said main outlet opening and having a passage adapted to register with said port in said wall means and to pass gas to said auxiliary outlet opening when said opening in said valve member and said port are in registry and during some of the movement of said valve member during which said opening in said valve member and said port do not register; a valve support in said housing; a resilient diaphragm extending across said housing and connected to said valve support; a resilient valve seat on said diaphragm; a valve disc engaging said support and adapted upon the application of a predetermined pressure for snapping from closed position in sealing engagement with said valve seat wherein it closes communication between said inlet opening and said main outlet opening to open position free of said valve seat permitting communication between said inlet opening and said main outlet opening; a control member movable in response to temperature variations; motion multiplying means comprising a plurality of interengaging levers transmitting the movement of said control member to said valve disc so long as the resistance to movement of said disc is less than a predetermined value and adapted for multiplying the movement of said control member during such transmission; relief means associated with said motion multiplying means limiting the motion transmitted by said motion multiplying means; and operating means exterior of said housing adapted for moving said valve member to position in which said passage therein permits communication between said inlet opening and said auxiliary outlet opening and for moving said valve member and said valve support whereby the temperature of said control means at which said valve disc is snapped to open position is varied.

3. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a

valve support in said housing; a valve seat in said housing; a second valve means in the form of a snap valve disc engaging said support and adapted upon the application of a predetermined pressure for snapping by its own resilience from closed position in sealing engagement with said valve seat and closing communication between said openings in said housing to open position free of said valve seat and permitting communication between said openings in said housing; a control member movable in response to temperature variations; motion multiplying means transmitting the movement of said control member to said valve disc so long as the resistance to movement of said disc is less than a predetermined value; and operating means exterior of said housing adapted for simultaneously moving said first valve means and said valve support whereby the movement of said first valve means is controlled and the temperature of said control member at which said valve disc is snapped to open position is varied.

4. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a valve support in said housing; a valve seat in said housing; a second valve means in the form of a snap valve disc having a yielding concavo-convex construction, engaging said support and adapted upon the application of a predetermined pressure for snapping by its own resilience from closed position in sealing engagement with said valve seat and closing communication between said openings in said housing to open position free of said valve seat and permitting communication between said openings in said housing; a control member movable in response to temperature variations; motion multiplying means transmitting the movement of said control member to said valve disc so long as the resistance to movement of said disc is less than a predetermined value; and operating means exterior of said housing adapted for moving said first valve means and said valve support whereby the movement of said first valve means is controlled and the temperature of said control member at which said valve disc is snapped to open position is varied.

5. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a valve support in said housing; a valve seat in said housing; a second valve means in the form of a deformable concavo-convex snap valve disc engaging said support and adapted upon the application of a predetermined pressure for snapping by its own deformation from closed position in sealing engagement with said valve seat and closing communication between said openings in said housing to open position free of said valve seat and permitting communication between said openings in said housing; a control member movable in response to temperature variations; motion multiplying means transmitting the movement of said control member to said valve disc; and operating means exterior of said housing adapted for moving said first valve means and said valve support whereby the movement of said first valve means is controlled and the temperature of said

control member at which said valve disc is snapped to open position is varied.

6. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a valve support in said housing; a valve seat in said housing; a second valve means in the form of a snap valve disc having a deformable snapping construction and engaging said support and adapted upon the application of a predetermined pressure for snapping by reason of its own construction from closed position in sealing engagement with said valve seat and closing communication between said openings in said housing to open position free of said valve seat and permitting communication between said openings in said housing; a control member movable in response to temperature variations; motion multiplying means transmitting the movement of said control member to said valve disc so long as the resistance to movement of said disc is less than a predetermined value; and operating means exterior of said housing adapted for moving said first valve means whereby the movement of said first valve means is controlled and for thereafter moving said valve support whereby the temperature of said control member at which said valve disc is snapped to open position is varied.

7. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a valve support in said housing; a valve seat in said housing; a second valve means in the form of a deformable inherently resilient snap valve disc engaging said support and adapted upon the application of a predetermined pressure for snapping by its own resilience from closed position in sealing engagement with said valve seat and closing communication between said openings in said housing to open position free of said valve seat and permitting communication between said openings in said housing; a control member movable in response to temperature variations; motion multiplying means transmitting the movement of said control member to said valve disc; and operating means exterior of said housing adapted for moving said first valve means whereby the movement of said first valve means is controlled and for thereafter moving said valve support whereby the temperature of said control member at which said valve disc is snapped to open position is varied.

8. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a valve support in said housing; a resilient valve seat in said housing; a second valve means in the form of a snap valve disc engaging said support and adapted upon the application of a predetermined pressure for snapping from closed position in sealing engagement with said valve seat and closing communication between

said openings in said housing to open position free of said valve seat and permitting communication between said openings in said housing; a control member movable in response to temperature variations; motion multiplying means transmitting the movement of said control member to said valve disc so long as the resistance to movement of said disc is less than a predetermined value; and operating means exterior of said housing adapted for moving said first valve means and said valve support whereby the movement of said first valve means is controlled and the temperature of said control member at which said valve disc is snapped to open position is varied.

9. In a thermostatically controlled valve mechanism, the combination of: a housing having inlet and outlet openings therein; wall means in said housing between said openings; a first valve means associated with said wall means and controlling the passage of fluid between said openings by movement between closed and open positions; a valve support in said housing; a valve seat in said housing; a second valve means in the form of a snap valve disc engaging said support and adapted upon the application of a predetermined pressure for snapping from closed position in sealing engagement with said valve seat and closing communication between said openings in said housing to open position free of said valve seat and permitting communication between said openings in said housing; a control member movable in response to temperature variations; motion multiplying means transmitting the movement of said control member to said valve disc so long as the resistance to movement of said disc is less than a predetermined value; relief means associated with said motion multiplying means limiting the motion transmitted by said motion multiplying means to said valve disc; and operating means exterior of said housing adapted for moving said first valve means and said valve support whereby the movement of said first valve means is controlled and the temperature of said control member at which said valve disc is snapped to open position is varied.

10. In a thermostatically controlled valve mechanism, the combination of: a housing having inlet and main and auxiliary outlet openings therein; wall means in said housing between said inlet and main outlet openings, said wall means having port means therein; a valve member having passages therein, said valve member engaging said wall means and being movable relative thereto for varying the registration of said port means and said passages, said passages being so related that registration with said port means opens communication between said inlet and said auxiliary outlet opening before and while said inlet and said main outlet openings are in communication through said port means; a valve support in said housing; a valve seat in said housing; a valve disc engaging said support and adapted upon the application of a predetermined pressure for snapping from closed position in sealing engagement with said valve seat and closing communication between said inlet and main outlet openings in said housing to open position free of said valve seat and permitting communication between said inlet and main outlet openings in said housing; a control member movable in response to temperature variations; motion multiplying means transmitting the movement of said control mem-

ber to said valve disc so long as the resistance to movement of said disc is less than a predetermined value; and operating means exterior of said housing adapted for moving said valve member and said valve support whereby the registration of said opening in said valve member with said port in said wall means is controlled and the temperature of said control member at which said valve disc is snapped to open position is varied.

11. In a thermostatically controlled valve mechanism, the combination of: a housing having inlet and outlet openings thereon; wall means in said housing between said openings; valve means associated with said wall means and controlling the passage of fluid between said openings by movement between closed and open position; a valve support in said housing; a resilient valve seat in said housing; a second valve means engaging said support and yieldably engaged by said resilient valve seat when in closed position and adapted upon the application of predetermined pressures for sudden movements to and from closed position in engagement with said valve seat, whereby to open and close communication between said inlet and outlet openings; a control member movable in response to temperature variations, having a connection with said second valve means to cause said sudden movements to and from said closed position; and operating means exterior of said housing adapted for moving the first valve means and said valve support whereby the movement of said first valve means is controlled and for controlling the temperature at which said control member is actuated to control movement of said second valve means.

12. A combination according to claim 11 wherein said resilient valve seat is located at the inlet side of said second valve means.

13. A combination according to claim 7 wherein the valve seat is of yielding construction adapted to conform to the edges of said deformable valve disc when engaged thereby.

JAMES MAYNARD.
